UNITED STATES PATENT OFFICE.

JOHN J. DREW, OF CHICAGO, ILLINOIS.

CALLOUS REMOVER.

Application filed May 11, 1923. Serial No. 638,225.

To all whom it may concern:

Be it known that I, JOHN J. DREW, a citizen of the United States, and a resident of the city of Chicago, in the county of Cook 5 and State of Illinois, have invented certain new and useful Improvements in a Callous Remover; and I do hereby declare that the following is a full, clear, and exact description of the same, reference being had to the 10 accompanying drawings, and to the numerals of reference marked thereon, which form a part of this specification.

This invention relates to an improved type of a callous remover constructed with a cutter 15 blade, against which a spring controlled pivoted guard is adapted to engage in such a way that when the callous remover is applied to a callous portion, the guard will be adjusted to control the depth of cut.

It is an object of this invention to provide 20 a callous remover wherein the opening in the base plate into which the cutter blade projects is closed by a spring controlled pivoted guard plate which overlaps the cutting edge 25 of the cutter blade and is adapted to be moved away from said cutting edge by the callous to be cut.

It is also an object of the invention to provide 30 a callous remover having a hood for receiving the cuttings and removable for emptying when a removable side of the callous remover housing is removed.

It is a further object of the invention to 35 provide a callous cutter of simple and effective construction adapted for shaving off callouses, and further adapted to be readily opened up to permit cleaning thereof and removal of the cutter blade and the blade guard when necessary.

Other and further important objects of 40 this invention will be apparent from the disclosures in the specification and accompanying drawings.

This invention (in a preferred form) is 45 illustrated in the drawings and hereinafter more fully described.

On the drawings:

Figure 1 is a front end elevation of a 50 callous remover embodying the principles of this invention.

Figure 2 is a bottom plan view thereof.

Figure 3 is a side elevation of the callous remover with the removable side taken off.

Figure 4 is an enlarged longitudinal de-

tailed section taken on line 4—4 of Figure 1, 55 showing the cutter blade in elevation.

Figure 5 is a transverse sectional view taken on line 5—5 of Figure 4.

As shown on the drawings:

The reference numeral 1 indicates a housing provided with a pocket 2. One side of the housing 1 is permanently closed by a side member 3, which is rigidly secured in place by welding, soldering, or any other suitable means. The opposite side of the housing 1 is open and is adapted to be closed by a removable side member 4. The rear end of the housing 1 is enlarged to receive a longitudinally split cylindrical sleeve 5 rigidly secured transversely therein. The two sides 3 and 4 of the housing are straight at the bottom flanges which extend slightly below the flat bottom plate 6 of the housing, as shown at 7. If desired, the bottom flanges of the side plates may be flush with the bottom plate 6. The flat bottom 6 is provided with a transverse opening 8, into which the cutting edge of a cutter blade 9 projects. The cutter blade 9 is positioned within the housing 1 and has the inner end thereof projecting through the slot 10 in the split sleeve 5 (Figure 4). The blade 9 is provided with longitudinal slots, through which set screws 11 project to hold cross bars 12 in set positions on opposite sides of the blade with one of said bars disposed in the sleeve 5 and the other bar positioned on the outside of the sleeve.

Removably engaged transversely in the lower front portion of the housing pocket 2 is a rotatable pin 13, to which is secured a guard plate 14 adapted to be resiliently held against the upper surface of the lower or cutting end of the blade 9. To resiliently hold the guard 14 against the blade 9 a spring 15 is secured to the pin 13 with the free end engaged against the inner surface of the top wall of the housing 1, as illustrated in Figure 3. The pin 13, the guard plate 14, and the spring 15, are removable from the housing as a unit when the side member 4 is removed. The blade 9 may also be removed from the housing 1 and the screws 11 released to permit the bars 12 to be adjusted so that the blade 9 may be adjusted with respect to the opening 8 in the bottom plate 6 of the housing.

The pocket 2 opens through the top of the

housing 1. As illustrated in Figure 4, the top of the housing is provided with two transverse beads or slotted guides 16 to slidably receive the ends of a hood or cover 17, which is removably engaged on the top of the housing 1 over the pocket 2 to receive the cuttings or shavings cut off by the blade 9 when the callous remover is used. The hood 17 is retained in place by the removable side member 4.

The safety callous remover is shaped to be conveniently gripped by the hand of a user, and is adapted to be worked back and forth over a callous to shave off portions of the same without danger of cutting the flesh. When the bottom opening 8 of the callous remover reaches the calloused portion which is to be removed, the callous projects into said opening and against the spring-impelled guard plate 14, which is consequently swung inwardly against the action of the spring 15 an amount depending upon the pressure applied by the user. The amount of opening between the cutter blade 9 and the guard plate 14 determines the thickness of the cut taken by the callous remover. The shavings cut off by the callous remover are forced into the pocket 2 and are prevented from falling out by the hood 17. When it becomes necessary to empty the callous remover the same is inverted and the side 4 removed. The hood 17, into which the shavings have fallen, is now pushed out of the open side of the housing and may be emptied. The cutter blade 9 may be adjusted by adjusting the cross bars 12 by simply loosening the set screws 11. The blade 9 is readily removed from the housing when the side member 4 is removed from the housing.

I am aware that numerous details of construction may be varied through a wide range without departing from the principles of this invention, and I therefore do not purpose limiting the patent granted otherwise than necessitated by the prior art.

I claim as my invention

1. A callous remover comprising a housing having an opening in the bottom thereof and a pocket in said housing communicating with said opening, a split sleeve secured in said housing, a blade having one end projecting into said split sleeve and the other end projecting into said bottom opening to afford a cutting edge, and a spring-impelled guard plate pivotally mounted in said pocket to close said opening and resiliently engage against said blade.

2. A callous remover comprising a housing having a bottom opening and a pocket communicating with one another, a split sleeve rigidly secured in said housing, a blade in said housing projecting into the split sleeve and into said opening below the pocket, means on said blade to permit ad-

justment thereof, a guard plate pivotally mounted in said pocket, and a spring in said housing for resiliently holding the guard plate against said blade to close said opening.

3. A callous remover comprising a housing having an opening in the bottom thereof, a split sleeve secured in said housing, a cutter blade in said housing projecting into the split sleeve and into said opening, and means on said blade for holding the same in place.

4. A callous remover comprising a housing having an opening in the bottom thereof, a split sleeve disposed transversely in said housing, a blade in said housing projecting into the split sleeve and into said opening, means on the blade for holding the blade in an adjusted position, and a spring-impelled plate pivoted in said housing and resiliently engaging said blade.

5. A callous remover comprising a housing having an opening in the bottom thereof, a split member in said housing, a blade in said housing having one end projecting into said split member and the other end projecting into said opening, a guard plate pivoted in said housing, a spring for holding the guard plate against said blade, and a hood on said housing.

6. A callous remover comprising a housing having an opening and a pocket therein, a sleeve secured in said housing having a slot therein, a blade in said housing projecting into said opening and into the sleeve slot, means on said blade for holding the same in a set position of adjustment, a guard plate pivoted in said housing to close the opening therein, a spring for resiliently holding the guard plate pressed against the blade, guides formed on said housing, and a hood removably engaged in said guides to cover the housing pocket.

7. A callous remover comprising a housing having an opening and a pocket therein, said housing being open at one side, guides on said housing, a hood slidably in said guides to cover the housing pocket, a split sleeve secured in said housing, a blade in said housing projecting into the split sleeve and into the housing opening, means on the blade adapted to engage the split sleeve to hold the blade in an adjusted position, a guard plate pivoted in said housing, a spring connected with the guard plate for holding the same against the blade and closing said opening, and a removable side member for closing the open side of the housing and holding the hood in place.

8. A callous remover comprising a housing having a flat bottom provided with an opening, a blade in said housing projecting into said opening, and a spring controlled guard plate pivoted in said housing and resiliently pressing against the blade.

9. A callous remover comprising a housing open at one side, guides on said housing, a hood for said housing slidable in said guides, and a side member for closing the 5 open side of the housing and holding the hood in place.

10. A callous remover comprising a housing open at one side, a cutter therein, guides formed on said housing, a hood slidable in 10 said guides, and a side plate for closing the

open side of the housing and holding the hood in place.

In testimony whereof I have hereunto subscribed my name in the presence of two subscribing witnesses.
